(57) **CLAIM**

The ornamental design for a mounting system for a roof rack for a vehicle, as shown and described.

DESCRIPTION

FIG. 1 is a front perspective view of a mounting system according to the present disclosure;

FIG. 2 is a rear perspective view thereof;

FIG. 3 is a top perspective view thereof;

FIG. 4 is a front elevation view thereof;

FIG. 5 is a rear elevation view thereof;

FIG. 6 is a right elevation view thereof;

FIG. 7 is a left elevation view thereof;

FIG. 8 is a top plan view thereof; and,

FIG. 9 is a bottom plan view thereof.

The broken lines in the drawings illustrate portions of the mounting system for a roof rack for a vehicle that form no part of the claimed design.

1 Claim, 9 Drawing Sheets
